(57) **CLAIM**

The ornamental design for a split wing golf ball, as shown and described.

DESCRIPTION

FIG. 1 is a perspective view of the split wing golf ball showing my design;

FIG. 2 is a front view of the split wing golf ball;

FIG. 3 is an opposing rear side view of the split wing golf ball;

FIG. 4 is a left side view of the split wing golf ball;

FIG. 5 is an opposing right side view of the split wing golf ball;

FIG. 6 is a top view of the split wing golf ball; and,

FIG. 7 is an opposing bottom view of the split wing golf ball.

The broken lines shown in FIGS. 1–7 are for illustrative purposes only and form no part of the claimed design.

1 Claim, 1 Drawing Sheet
